United States Patent

Des. 236,641
Patented Sept. 2, 1975

236,641

TOY AIRPLANE

Hans J. Meffert, Michelet 43-7, Mexico City 5, Mexico

Filed Jan. 3, 1974, Ser. No. 430,467

Term of patent 14 years

Int. Cl. D21—01

U.S. Cl. D34—15 HH

FIG. 1 is a top plan view of a toy airplane embodying the new design;

FIG. 2 is a bottom plan view;

FIG. 3 is a view in front elevation;

FIG. 4 is a view in rear elevation; and

FIG. 5 is a view in side elevation.

I claim:

The ornamental design for a toy airplane, substantially as shown and described.
